UNITED STATES PATENT OFFICE.

WALTER S. RYAN, OF NEW YORK, N. Y.

SIGN-FLASHING MECHANISM.

1,100,917.

Specification of Letters Patent. Patented June 23, 1914.

Application filed October 28, 1912. Serial No. 728,165.

To all whom it may concern:

Be it known that I, WALTER S. RYAN, a citizen of the United States of America, and residing at New York, in the county of New York and State of New York, have invented new and useful Improvements in Sign-Flashing Mechanism, of which the following is a specification.

The invention relates particularly to electric light circuit controlling mechanism.

The main object is to provide a simple and inexpensive mechanism by means of which the circuit may be opened and closed automatically with a minimum amount of arcing and consequent heating.

In the preferred embodiment of the invention a resilient brush is adapted to be engaged by a rotating segment for making and continuing the circuit. The circumferential extent of this segment and speed of rotation determine the period of time through which the circuit is energized. The angular adjustment of the segment on its shaft determines the time when the circuit is made and broken.

The special object of the invention is to break the circuit quickly and minimize arcing. This is accomplished by providing an auxiliary contact member which is carried by the contact segment and adapted to move relative thereto being under spring tension. As the contact segment rotates this auxiliary contact engages the brush and as the auxiliary contact snaps out from under the brush, the brush snaps across the path of movement of the contact segment and the auxiliary contact snaps across the path of movement of the brush, all this while the segmental contact is rotating.

Figure 1, shows one form of mechanism embodying the improvements of my invention, the brush resting on the segment contact which rotates in the direction of the arrow. Fig. 2, shows the contacts with the brush resting on the auxiliary contact. Fig. 3, shows the contacts in the positions which they occupy when the auxiliary contact snaps from beneath the brush. Fig. 4, is a perspective view of the auxiliary contact member. Fig. 5, shows another form of an auxiliary contact construction, the brush resting on the segmental contact. Fig. 6, is a view of the elements of Fig. 5, the brush resting on the auxiliary contact. Fig. 7, is a plan view of the segmental and auxiliary contact members of Figs. 5 and 6.

The brush 1 illustrated in the drawing is of the common laminated metallic strip type supported by a suitable holder 2. The strips may be secured together near their outer ends if desired for instance, by means of a clip 3 and an abutment 4 may be provided to limit the downward throw of the brush. A rotatable contact segment 5 is secured on the shaft 6 by means of a set screw 7 or other suitable device so that the segment is insulated from the shaft but may be given its proper angular adjustment on the shaft. While I have illustrated but one segment it is obvious that any number may be provided on the shaft 6 and adjusted to give the desired sequence of operation. A contact drum 8 is also shown and is mounted on the shaft 6 and which is engaged by the usual form of brush (not shown). The brush holder and the shaft are all carried by a suitable framework 9 so as to preserve their proper relative positions. A worm gear 10 carried by the shaft 6 meshes with the worm 11 which is on the shaft 12 with the pulley 13. The motor 14 with a driving pulley 15 and belt 16 is illustrated as one means for driving the shaft 6 and its contact segments usually continuously in one direction.

The auxiliary contact 17 is mounted on the pivot 18 carried by the web of the contact segment 5 and has an arm 19 extending inward from the outer contact end. A spring 20 has one end secured to the contact segment and the other end secured to the arm 19 so as to normally hold the auxiliary contact member in the position shown in Fig. 1. As the contact segment rotates in the direction of the arrow it comes into the position shown in Fig. 2, with the brush resting on the outer face of the auxiliary contact member 17. The tension of the spring 20 is such that the pressure of the brush on the auxiliary contact 17 moves the outer contact end inward against the tension of the spring 20. As the contact segment 5 continues to rotate in the direction of the arrow, the auxiliary contact 17 snaps out from under the end of the brush into the position shown in Fig. 3 in full lines and then into the position shown in dotted lines. I prefer to provide two insulating blocks 21 and 22 carried respectively by the brush and the auxiliary contact member so as to intersect the arc which may be formed between the end of the brush and the contact member as the

parts pass through the positions shown in Fig. 3. This means that the arc which would normally tend to draw out between the end of the contact segment and the brush 5 must form between the end of the brush and the end of the auxiliary contact member 17. As the auxiliary contact moves outward to the position shown in Fig. 3 with a quick snap action the arc is much more quickly 10 and extensively elongated and therefore more thoroughly broken. By interposing the insulating blocks 21 and 22 the arc is mechanically intercepted and completely extinguished.

15 In order that the circuit may be more quickly and completely made I prefer to provide an insulating tip 23 for instance, of porcelain which is secured beneath the contact flange of the contact segment 5 and 20 extends around the end. As the contact segment rotates in the direction of the arrow, the insulated tip 23 engages beneath the end of the brush 1 and lifts it. As the contact segment and tip 23 continue to rotate, the 25 end of the brush snaps off the outer edge of the tip 23 and down on to the contact surface of the segment 5.

In the form shown in Figs. 5, 6 and 7 the contact segment 25 has an auxiliary contact member 26 with side flanges 27, 27 mounted on the hub of the main contact segment. A spring 28 holds the auxiliary contact yieldingly in the position shown in Fig. 5. As the contact segment rotates in 35 the direction of the arrow, the brush 1 engages the auxiliary contact portion 26 which is thus frictionally retarded while the main portion of the contact segment 25 continues to rotate. The segment 25 is provided with 40 a stop 29 and the auxiliary contact member is provided with a set screw 30 adapted to engage the stop 29 so that when the stop 29 engages the set screw 30 the auxiliary contact member again starts to rotate with the 45 contact segment until the auxiliary contact snaps from beneath the brush, the parts assuming the dotted line positions of Fig. 6. In this construction it will be noted that the quick relative movement of the auxiliary 50 contact member greatly accelerates the break. While I have shown the insulating blocks 21 and 22 in Fig. 5 they may be omitted as shown in Fig. 6.

The contact face of the auxiliary contact member 17 may be made separate and secured by a screw 31 and detachable from the body so as to be readily replaced if desired. The insulating block 22 and the contact face may be both clamped by the same 60 screw in a slot 32 (see Fig. 4).

What I claim is:

1. In a sign flashing device, a rotating contact segment, an auxiliary contact member carried by said contact segment and movable relative thereto, a brush for engaging

said contact segment and said auxiliary contact and means for moving said auxiliary contact relative to said contact segment when disengaged from said brush.

2. In a sign flashing mechanism, a rotating contact segment, an auxiliary contact member pivotally carried thereby, a brush for coacting with said contact segment and said auxiliary contact and a spring for moving said auxiliary contact member relative to 75 said contact segment when disengaged from said brush.

3. In a sign flashing mechanism, a rotating contact segment, an auxiliary contact carried by said contact segment and movable therewith and also having a limited movement in a direction transverse to the direction of movement of the contact surface of said segment, a contact brush adapted to engage said segment and said auxiliary contact and having a direction of movement 80 transverse to the direction of movement of the contact face of said segment and opposite to the direction of movement of said auxiliary contact, and means for snapping 85 the auxiliary contact in a direction away from the movement of the contact brush as the brush snaps from the auxiliary contact.

4. In a sign flashing device, a rotating contact segment, an auxiliary contact member carried by said contact segment and movable relative thereto, a brush for engaging said contact segment and said auxiliary contact, means for moving said auxiliary contact relative to said contact segment when 100 disengaged from said brush and means for intercepting the arc.

5. In a sign flashing mechanism, a rotating contact segment, an auxiliary contact member pivotally carried thereby, a brush for coacting with said contact segment and said auxiliary contact, a spring for moving said auxiliary contact and means for intercepting the arc.

6. In a sign flashing mechanism, a rotating contact segment, an auxiliary contact member carried by said contact segment and movable therewith and also having a limited movement in a direction transverse to the direction of movement of the contact surface of said segment, a contact brush adapted to engage said segment and said auxiliary contact and having a direction of movement 115 transverse to the direction of movement of the contact face of said segment and opposite to the direction of movement of said auxiliary contact and means for intercepting the arc.

7. In a sign flashing device, a rotating contact segment, an auxiliary contact member carried by said contact segment and movable relative thereto, a brush for engaging said contact segment and said auxiliary contact, means for moving said auxiliary contact relative to said contact segment when dis- 125 130

engaged from said brush and insulating blocks carried by said auxiliary contact and by said brush for intercepting the arc.

8. In a sign flashing mechanism, a rotating contact segment, an auxiliary contact member pivotally carried thereby, a brush for coacting with said contact segment and said auxiliary contact, a spring for moving said auxiliary contact member and insulating blocks carried by said auxiliary contact and by said brush for intercepting the arc.

9. In a sign flashing mechanism, a rotating contact segment, an auxiliary contact member carried by said contact segment and movable therewith and also having a limited movement in a direction transverse to the direction of movement of the contact surface of said segment, a contact brush adapted to engage said segment and said auxiliary contact and having a direction of movement transverse to the direction of movement of the contact face of said segment and opposite to the direction of movement of said auxiliary contact and insulating blocks carried by said auxiliary contact and by said brush for intercepting the arc.

10. In a sign flashing mechanism, a rotating contact segment, an auxiliary contact pivotally carried thereby and having a contact surface adapted to be projected beyond the circumference of said segment, a contact brush for engaging said segment and said auxiliary contact and means for snapping the auxiliary contact relative to said contact segment when disengaged from said brush.

11. In a sign flashing mechanism, a rotating contact segment, an auxiliary contact member pivotally carried thereby and having a contact surface adapted to be projected beyond the circumference of said segment and a contact brush for engaging said segment and said auxiliary contact and means for intercepting the arc.

12. In a sign flashing mechanism, a rotating contact segment, an auxiliary contact member pivotally carried thereby and having a contact surface adapted to be projected beyond the circumference of said segment and a contact brush for engaging said segment and said auxiliary contact and blocks carried by said brush and auxiliary contact for intercepting the arc.

13. In a sign flashing device, a rotating contact segment, an auxiliary contact member carried by said contact segment and movable relative thereto, a brush for engaging said contact segment and said auxiliary contact and means for moving said auxiliary contact relative to said contact segment when disengaged from said brush, said auxiliary contact member having a detachable contact face.

14. A rotatable contact segment, an extension contact movably carried thereby, means for rotating said contact segment and its extension, a resilient contact brush adapted to bear upon said contact segment and upon its extension contact as the contact segment rotates and a spring connecting said segment to a part of said extension for moving said extension contact relative to said segment when the resilient contact brush snaps from said extension to thereby accelerate the breaking of the arc.

15. In a sign flashing mechanism, a rotating contact segment, an auxiliary contact member carried thereby and movable relative thereto and having a detachable contact face and a brush coacting with said segment and said contact face and an insulating block connected to said contact face for intercepting the arc.
